Thomas Howe

UNITED STATES PATENT OFFICE

IGNAZ SABLÍK, OF STRAMBERG, CZECHOSLOVAKIA

LIQUID FEEDING APPARATUS

Application filed January 4, 1930, Serial No. 418,457, and in Czechoslovakia January 19, 1929.

This invention relates to a method of feeding liquids composed of certain chemical elements, or containing solids in suspension. Considerable trouble is caused in feeding liquids containing certain elements due to their corrosive action on the reciprocating or the rotary parts of the pump. Also difficulty is encountered when feeding liquids containing solids in suspension, due to clogging of the parts of the pump with which it contacts.

One of the objects of this invention is to overcome these difficulties by providing an improved method of feeding liquids composed of certain chemical elements or containing solids in suspension, so that the liquid to be fed does not come in contact with either the reciprocating or the rotary parts of the pump.

Another object of the invention is to provide an improved and simple valve operating mechanism for feeding liquids wherein the direct influence of air pressure of variable strength is utilized in moving the fluid to be fed.

25. This is accomplished by providing two reservoirs each fitted with a suction connection to the liquid to be fed, and a connection for discharging the liquid. These reservoirs are alternately and by turns connected to the suction and pressure pipes of a compressor, so that when one reservoir is being filled with the liquid to be fed, the other reservoir is being emptied. In this manner the liquid to be fed does not come into contact with either the reciprocating or the rotary parts of the pump.

Other and ancillary objects of the invention will appear hereinafter.

In the accompanying drawings which embody the invention—

40. Fig. 1 is a front elevation of apparatus embodying the invention partly in section; and

Fig. 2 is a side elevation of the apparatus of Fig. 1.

45. Referring to the drawings, reservoirs 1 and 2 are both provided at the bottom with a distributor 3, connected at 4 to the suction piping and at 5 to the discharge piping. The suction piping 4 is connected to the liquid to be fed, which liquid is discharged through

the discharge piping 5 to the place where it is desired to feed the liquid.

Both the suction and discharge piping contain appropriate members not shown, allowing the passage of the liquid in one direction only. In the top of reservoir 1 is shown a branch of pipe 6 which connects with reservoir 2 through a branch 7 and valve 15. In both reservoirs are located the floats 8 and 9 having a central opening 10 which slides upon the guide rod 11. When the reservoir is empty the float is supported on the guide-rod stop 12, but when the reservoir is being filled, the float is lifted by the liquid and rises until it strikes a disk 13, secured to the guide-rod and lifts the rod. On the upper end of the guide is secured the valve 14, so that the lifting of this rod seats the valve and closes the reservoir from the line 6. Similarly the float 9, in reservoir 2, disconnects this reservoir from the branch 7. Each reservoir can be connected alternately to a suction line 16 or to a pressure line 17 of a compressor system, by means of a two-way valve 15. With either one of the reservoirs filled and the valve 14 seated, if pressure is exerted above the valve, from the pressure line 17, the valve will be unseated and the liquid forced from the reservoir so as to enter the discharge pipe 5 through the distributor 3. By means of the two-way valve 15, and its connections, hereinafter described, while the one reservoir is being emptied by the pressure from the pressure line, the other reservoir is connected with the suction line 16, and is being filled.

The two-way valve 15 is operated by the piston 18 of the pressure cylinder 19 through the lever 20 which is fastened to the valve. Both sides of the cylinder 19 are connected with the compressor system and to the pressure line, by means of a pipe 21, and the annular pipe 22. In order that the piston 18 may operate and reverse the valve 15, the medium operating in the cylinder must be exhausted above the piston and at the same time be admitted below the piston and vice versa to reverse it. The control of the medium to cause reversal is accomplished by means of the valves 23 and 24 inserted in the

annular pipe 22. These valves are of the three-way type and alternately allow pressure to flow to cylinder 19 and permit the exhaust therefrom. These valves are operated by the guide-rods 11, through the levers 25 and 26, passing through slots arranged in the guide-rods. The spiral springs 27 are secured to the rods 11 and assist the valve 14 to operate smoothly and efficiently. A check valve 28 is placed between the pressure end 17 of the compressor and the two-way valve 15 to prevent the compressor medium from flowing back into the system. When the two-way valve 15 has reached the position in which the reservoir 1 is to be filled and the reservoir 2 is to be emptied, the medium such as the air carried by the compressor on the suction end, flows in the direction of the arrow I, and the medium carried on the pressure end flows in the direction of the arrow II. When reversal has taken place the direction of the medium actuated by the compressor, is shown on the suction end, by the arrow III, and on the pressure side by the arrow IV. Reservoir 1 is thus being emptied while the reservoir 2 is being filled.

Other methods may be used to effect the reversal of the two-way valve 15, for example by electricity, controlled by contacts 30 on and operated by the guide-rods 11. Instead of one two-way valve inserted between the two reservoirs there could be used two such valves, and even four governing members could be used as follows: Two, to control 35 the inlet and outlet of one reservoir, and two to control the same valves in the other reservoir.

While the invention has been illustrated in what is considered its best application it may 40 have other embodiments without departing from its spirit and is not, therefore, limited to the structures shown in the drawings.

What I claim is:

1. In a liquid feeding apparatus, the combination with two tanks each having intake and discharge openings at the bottom, suction and pressure pipes, ducts leading from said suction and pressure pipes to said tanks, a valve adapted to alternately connect said pressure and suction pipes with each of said tanks, one of said tanks being connected with the suction pipe when the other tank is connected with the pressure pipe, a pressure cylinder having a piston operatively related to said valve, valves for controlling the admission of pressure to said pressure cylinder, a valve in each of said tanks controlling the communication of the tank with said ducts and floats in said tanks controlling the last mentioned valves and valves controlling the admission of pressure to said pressure cylinder.

2. In a liquid feeding apparatus, the combination with two tanks each having intake and discharge openings at the bottom, suc-

tion and pressure pipes, ducts leading from said suction and pressure pipes to said tanks, a valve adapted to alternately connect said pressure and suction pipes with each of said tanks, one of said tanks being connected with the suction pipe when the other tank is connected with the pressure pipe, a pressure cylinder having a piston operatively related to said valve, valves for controlling the admission of pressure to said pressure cylinder, a valve in each of said tanks controlling the communication of the tank with said ducts, floats in the said tanks, guide-rods for said floats upon which the last mentioned valves are mounted, said guide-rods also operating the said valves for controlling the admission of pressure to said pressure cylinder.

3. In a liquid elevating apparatus the combination with two tanks, each having intake and discharge openings at the bottom, suction and pressure pipes, ducts leading from said suction and pressure pipes to said tanks, a valve operating cylinder containing a piston, a rotary valve exterior to said cylinder and operatively connected to said piston, said valve controlling the communication of said suction and pressure pipes with said tanks, a pipe adapted to connect said pressure pipe with said cylinder alternately on opposite sides of said piston, and two valves adapted to control the communication of said pressure pipe with said cylinder, guide-rods in said tanks adapted to operate the last mentioned valves and floats adapted to operate said guide-rods.

In testimony whereof I have signed my name to this specification.
